UNITED STATES PATENT OFFICE.

WILLIAM E. FOWLER, JR., OF MOUNT LEBANON, PENNSYLVANIA, ASSIGNOR TO
DAVIS BRAKE BEAM COMPANY, OF JOHNSTOWN, PENNSYLVANIA, A CORPORA-
TION OF PENNSYLVANIA.

SHOE FOR BRAKE-BEAM SUPPORTS.

Application filed May 15, 1924. Serial No. 713,559.

To all whom it may concern:

Be it known that I, WILLIAM E. FOWLER, Jr., residing at Mount Lebanon, in the county of Allegheny and State of Pennsylvania, a citizen of the United States, have invented or discovered certain new and useful Improvements in Shoes for Brake-Beam Supports, of which improvements the following is a specification.

It has been necessary to provide guiding supports supplementary to the usual hangers to ensure such positions of brake beams in order that the brake shoes may be properly applied to the wheels regardless of changes in the diameters due to turning down of the wheels. In general, the supplementary supports consist of shoes or carriers, as they are sometimes termed, interposed between some part of the brake beam and a supporting rail so secured to some part of the truck, usually the spring plank, and extending on both sides of the plank under the brake beam.

The invention described herein relates to an improved form of shoe adapted to be used as a member of what is known as a four-point type of brake beam support. The invention is hereinafter more fully described and claimed.

In the accompanying drawings forming a part of this specification, Fig. 1 is a plan view showing portions of the spring plank of a truck and a truss brake beam and supplemental supports embodying the improvements claimed herein; Fig. 2 is a side elevation showing the relative positions of the shoe, supporting rail and tension member of a brake beam; Fig. 3 is a side elevation of a modification of the construction of shoe, and Fig. 4 is a side elevation illustrating a further modification of the shoe as shown in Fig. 3.

In the practice of the invention the support rails 1 are secured to the spring plank 2 in such manner that rails will extend under the brake beam at points intermediate the strut 3 and the ends of the brake beam as shown in Fig. 1. As is usual, the portions of these rails adjacent to their ends are inclined upwardly and on such inclined portions are mounted the shoes which in turn support the brake beams.

The improved shoe consists of a block 4

having a slot or opening 5 therethrough for the reception of the supporting rail, along which the shoe will slide as the brake beam is shifted towards and from the wheel. On this block is mounted a saddle 6 U-shaped or open ended and arranged at an angle to the axis of the block which will correspond or be equal to the angle formed by the tension member with the supporting rail 1. It is preferred that the body or saddle portions should be made integral one with the other. This construction will permit of the easy removal of the brake beam from the shoe by a vertical movement of the beam or of the supporting rail and shoe without the employment of tools or the changing of the shape of any portion of the shoes. When the shoes are constructed as described and as shown in Fig. 2, they must necessarily be made rights and lefts on account of the opposite inclination of the portions of the tension member on opposite sides of the strut. For this reason, it is preferred to construct the shoe in the manner shown in Fig. 3. The block 4^a which is provided with a slot for the reception of the supporting rails as above described, has formed on opposite sides thereof, saddles 6^a arranged respectively at opposite angles to the axis of the block and hence the block can be used indiscriminately on one side or the other of the strut. While it is preferred that the block should be so constructed that the sides of the saddle will be at right angles to these supporting rails when the shoes are in position on the rails as shown in Figs. 2 and 3, they may be formed as shown in Fig. 4, in which case, when the shoes are in position on the rails the sides of the saddle will be at an acute angle to the supporting rail.

I claim herein as my invention:

1. A shoe for brake beam supports consisting of a base or body slotted for the reception of a supporting rail and provided with an open-topped seat for engagement with a portion of the brake beam.

2. A shoe for a supplemental support of a brake beam consisting of a body portion slotted for the reception of a supporting rail and provided on one side with an open-ended saddle for the reception of the tension member of a brake beam, said saddle

being arranged at an angle to the axis of the body portion corresponding to the angle of the tension member to the rail.

3. A shoe for a supplemental support of a brake beam consisting of a body portion slotted for the reception of a supporting rail and provided on opposite sides with

open-ended saddles for the reception of the tension member of a brake beam; said saddles being arranged at an angle to each ¹⁰ other and to the axis of the body portion.

In testimony whereof, I have hereunto set my hand,

WILLIAM E. FOWLER, JR.
